UNITED STATES PATENT OFFICE.

GARRISON BABCOCK, OF ROCHESTER, NEW YORK, ASSIGNOR TO TELECHRONOMETER COMPANY, OF ROCHESTER, NEW YORK, A CORPORATION OF NEW YORK.

TELEPHONE SYSTEM.

1,189,525.

Specification of Letters Patent. Patented July 4, 1916.

Application filed July 5, 1910. Serial No. 570,355.

To all whom it may concern:

Be it known that I, GARRISON BABCOCK, a citizen of the United States, residing at Rochester, in the county of Monroe and State of New York, have invented a certain new and useful Improvement in Telephone Systems, of which the following is a full, clear, concise and exact description, reference being had to the accompanying drawings, forming a part thereof.

My invention has for its object to provide a means at a substation on a party line at which a message meter and a time meter are located for permitting the apparatus to be used to determine whether the line is busy without actuating the message meter. The apparatus thus employed, while it permits the subscriber to hear the condition of the line does not, however, permit him to use the line without actuating such message meter. The time meter, on the other hand, is preferably connected so that continued listening in is registered.

My invention further provides a means by which the time meter or meters associated with a calling line cannot be actuated until the response of the called subscriber. Upon the response of the called subscriber the apparatus located at the exchange is actuated, which results in the connection of impulse-sending mechanism to the switching mechanism employed to connect the lines for conversation, and the impulses thus sent actuate the time meter or meters which may be operatively connected to the calling line during the connection with the called subscriber.

In addition to the devices already referred to, my invention further provides that after the called subscriber has effected an operative condition of the impulse-sending mechanism at the exchange further control of such impulse-sending mechanism is removed from the called subscriber during connection and transferred to the calling subscriber, which provides that the called subscriber, by actuating his hook switch, cannot repeatedly reverse the direction of current flow through the calling line and thus cause noise in the receiver of the calling subscriber and operate the time meter.

The time metering mechanism located at a substation is constructed so as to register the number of time units of service, which units are preferably of such a length as to

not require an excessive number of current reversals through the calling line for any particular connection and yet short enough to register with practical accuracy the length of time of any conversation. It has been found in practice that it is advisable to use a fractional part of a minute as the unit of time, such fractional part being inversely proportional to the distance, and the unit of service value thus measured is called a telechrene, which may be made up of different quantities of time and distance values.

Figure 1 is a diagrammatic circuit drawing of a telephone system, in accordance with my invention. Fig. 2 is a detail view of the message metering mechanism.

As shown in Fig. 1, the line wires 1, 2 extend to the substations A and A', while the line wires 3, 4 extend from the exchange to the substations B and B'. The substations A' and B' are indicated diagrammatically, but it is to be understood that each substation is preferably similarly equipped with talking and metering apparatus, as a result of which description of the apparatus located at a single substation is all that is necessary in this connection.

The line wires 1, 2 extend from the springs 5 and 6 of the jack J located at the exchange to the terminal posts 7 and 8, respectively, at the substation A, the line wire 2 having included serially therein at such substation a time meter 9 adapted to be actuated by current reversals in the line circuit, each reversal serving to advance the metering mechanism one unit. The post 7 is connected through the condenser 10 with the coils of the ringer 11, and also in parallel therewith to the spring 12 of the hook switch H. The post 8 is connected with the other terminal of the windings 11 of the ringer and also to the coils 13 and 14, which are the setting and actuating coils respectively of the message meter 15. The post 8 is also connected with the armature 16 of the ringer 11 and with the spring 17, adapted to be engaged by the spring 18 when the armature 19 of the message meter 15 is moved to its set position. The post 8 is also connected with the pivotal point of the switch 21. The spring 18 is connected with the other terminal of the resetting coil 18 and also to the contact 20 and one terminal of the transmitter T. The other terminal of the coil 14 is connected with a spring 22 adapted

110

to be moved into engagement with a spring 23 by the armature 19 when such armature is moved to its set position, the spring 23 being in turn connected with the spring 24 of the 5 hook switch H. The other terminal of the transmitter T is connected through the primary winding 25 of the induction coil with the spring 26 of the hook switch H. The springs 27 and 28 of the hook switch are connected together and also to the post 7. The 10 secondary winding 29 of the induction coil is connected in circuit with the receiver R in a manner well known in the art.

The terminals of the transmitter T have 15 secured thereto springs 30 and 31 adapted to be engaged by the upper end of the switch 21 when it is actuated, as a result of which the operation of such switch serves to short-circuit the transmitter and connect its terminals with the post 8, and thus with the line conductor 2.

The cord circuit employed in connection with my invention, as shown, consists of a 2-conductor cord, the tip strand consisting 25 of the sections 32 and 33, connected respectively with the tips 34 and 35 of the plugs P and P' and being separated by a condenser 36, as is usual in the art. The sleeve strand consists of the sections 37 and 38 30 connected respectively with the sleeves 39 and 40 of the plugs P and P', such sections being separated by a condenser 41. The sections 32 and 37 of the cord strands have connected therewith the relay magnets 42 and 43, which are the supervisory relays of the 35 answering end of the cord circuit, their other terminals being connected through wires 44 and 45 with the pivotal points of the armature 46 and 47 of the relay 48. The wire 44 40 has included serially therein the locking winding 49 of the relay 48. The strands 33 and 38 of the cord circuit have connected therewith the windings of the supervisory relay magnets 50 and 51, the other terminals 45 of which are connected by wires 52 and 53 with the positive and negative poles respectively of the battery 54. The wire 52 has serially included therein the main or actuating winding 55 of the relay 48. Sections 33 and 38 of the cord strands extend through 50 the ringing key K, by means of which current from the ringing generator G may be impressed upon the calling plug P' in a manner well known in the art. An operator's set O is connected with the strands 32 and 37 55 of the answering end of the cord to permit the operator to receive the order of the calling subscriber.

The armatures 46 and 47 of the relay 48 normally rest against the back contacts 56 and 57, connected by wires 58 and 59 with the negative and positive poles respectively of the battery 54. The wire 59 is also connected with the front contact 60 of the armature 46. The front contact 61 of the armature

47 is connected by wire 62 with the positive brush 63 of a generator G', the negative brush 64 of which is connected with wire 58 and thus to the negative pole of the battery 54. The generator G' is designed so 70 that it is energized, and this is accomplished periodically in the following manner: The winding of the field magnet 65 is connected by wires 66 and 67 through a controlling switch 68 with the brushes of a generator 75 69, adapted to properly energize the winding of the field magnet 65 when the switch 68 is closed. The switch 68 is controlled by an electromagnet 70 connected by wires 71 and 72 with the positive and negative poles 80 respectively of the battery 54. The wire 72 has included in it a commutator 73, rotated at a uniform rate by suitable time controlled mechanism, as a result of which the circuit through the magnet 70 is closed at regular 85 recurring intervals. The frequency and duration of such intervals of energization may obviously be made as desired by properly proportioning and rotating the commutator 73.

The operation of my invention is as follows: Assuming that the subscriber at substation A desires to call the exchange, he removes his receiver R from the hook switch H, thereby completing a circuit from battery 54 as follows: battery 54, wire 74, line relay 75, line wire 2, time meter 9, armature 16, contact 20, wire 75, wire 76, transmitter T, primary winding 25, spring 26, spring 27, wire 77, line wire 1, wire 78, and back to battery 54. Line relay 75 is thus energized and closes a circuit from battery 54 through the line signal 79, indicating to the operator at the exchange that a connection is desired. The operator thereupon inserts the plug P 105 in the jack J corresponding to the signal 79, which energizes the cut-off relay 80 by the following circuit: battery 54, wire 59, contact 57, armature 47, wire 45, sleeve supervisory relay 48, cord strand 37, sleeve 39, 110 ring 81 of jack J, winding of cut-off relay 80, wire 82, wire 78, and back to battery 54. At the same time that the circuit just described is closed and battery 54 is cut off from the line limbs 1 and 2, connection is 115 made from the battery 54 through the transmitter T at the substation A over the following circuit: battery 54, wire 59, contact 57, armature 47, wire 45, sleeve supervisory relay 48, cord strand 37, sleeve 39 of the 120 plug P, sleeve spring 6, line wire 2, time meter 9, post 8, armature 16; contact 20, wire 75, wire 76, transmitter T, primary winding 25, spring 26, spring 27, wire 77, post 7, line wire 1, tip spring 5, tip 34 of plug P, tip 125 supervisory relay 42, wire 44, locking winding 49 of relay 48, armature 46, contact 56, wire 58, and back to battery 54. The winding 49 is so proportioned that the current flowing therethrough at this time is insuffi- 130

cient to attract the armatures 46 and 47. The operator thereupon, by means of her telephone set O, learns the connection desired by the subscriber A, and, assuming that 5 the subscriber B is wanted, inserts the calling plug P' in the jack J', connected with the line conductors 3 and 4, extending to the substation B. The operator thereupon actuates the ringing key K, thus connecting the 10 generator G with the line limbs 3 and 4, and by a circuit similar to that traced for the substation A actuates the ringer 11 located at the substation B. The ringers 11 are all so constructed that when current does not 15 flow through them their armatures close the contacts 20 to short-circuit the terminals of the associated coils 13 of the message meters 15. Upon the response of the subscriber B a circuit is closed through the line limbs 3 and 20 4 as follows: battery 54, wire 52, energizing winding 55 of relay 48, tip supervisory relay 50, cord strand 33, tip 35 of plug P', line wire 4, to and through the apparatus at substation B by a circuit similar to that above 25 traced for the substation A, returning by line conductor 3, sleeve 40 of plug P', cord strand 38, sleeve supervisory relay 51, wire 53, and back to battery 54.

As a result of the flow of current through 30 the winding 55, the armatures 46 and 47 are attracted, thus connecting the supervisory relays 42 and 43 with the positive pole of the battery 54 and the positive brush of the generator G' respectively. Assuming that at 35 this time the circuit through the controlling magnet 70 is open, the current in the line circuit is reversed as follows: battery 54, wire 59, contact 60, armature 46, locking winding 49, wire 44, tip supervisory relay 42, tip 40 34, tip spring 5, line wire 1, through the apparatus at the substation A in the reverse direction to that above traced, returning by line wire 2, sleeve spring 6, sleeve 39, sleeve supervisory relay 43, wire 45, armature 47, 45 contact 61, wire 62, brush 63, armature of generator G', brush 64, wire 58, and back to battery 54. Thus the armature winding of the generator G' is included in circuit at this time, but as the field circuit is open 50 only the ohmic resistance of the armature is included, and this is so small as to have practically no effect upon the current flow.

It is to be noted that the current sent out 55 over the line wires 1 and 2 previous to the energization of the relay 48 causes a current flow through the windings of the ringer 11 as follows: line wire 2, time meter 9, post 8, coils of ringer 11, wire 83, spring 12, spring 28, wire 77, post 7, to the line wire 1.

It is to be noted that the direction of current flow through the coils of the ringer 11 60 is in the same direction during the signaling of the exchange by the substation A and during the connection of the answering end of the coil to the line wires 1 and 2 be-

fore the called subscriber has responded. This direction of current flow through the ringer 11 is in a direction tending to move the armature 16 against the contact 20 to hold the armature 16 in its normal position, 70 short-circuiting the resetting coil 13 of the message meter 15. When the relay 48 is energized, and, as above described, current flows from the positive pole of the battery 54 out over line conductor 1, it will be observed that the direction of current flow 75 through the ringer windings 11 is reversed, as a result of which the armature 16 is moved away from the contact 20, opening the short-circuit across the terminals of the coil 13, which thereupon receives current in a direction to move the left-hand end of the armature 19 downward to cause the armature to occupy its set position, for which 80 position the springs 17 and 18 are moved 85 into engagement with each other, thus again short-circuiting the coil 13 to prevent further operation of the armature 19, until the actuating coil 14 is energized. It is to be noted that the motion above described of the 90 armature 19 to its set position brings the springs 22 and 23 into engagement with each other, thus closing at one point the energizing circuit of the coil 14. The armatures 46 and 47 are held in their attracted 95 position as long as the switch hook at the substation B is in its raised or talking position, and even if the switch be subsequently moved to its normal position, opening the circuit through the supervisory relay 50 and 100 the energizing winding 55, the locking winding 49 is so proportioned as to retain the armatures 46 and 47 in their attracted position as long as the current flows through such locking winding, due to the switch hook 105 at the substation A being in its upper or talking position.

After the relay 48 has been energized and during the time that the armatures 46 and 47 are held in their attracted position, the 110 armature of the generator G' is retained in the circuit above described. The generator G' is so constructed as to produce an electromotive force about twice that of the battery 54, and since its negative brush 64 is 115 connected with the negative terminal of the battery 54, the electromotive force developed is partly consumed in charging the battery 54 during the intervals that the field 65 is 120 energized, the remaining portion of the electromotive force developed by the generator G' being impressed upon the circuit in which its armature is connected as follows: positive brush 63, wire 62, contact 61, armature 47, wire 45, relay 43, sleeve 39, sleeve spring 6, 125 line wire 2, to and through the apparatus at the substation A, returning by line wire 1 to tip spring 5, tip 34, relay 42, wire 44, locking winding 49, armature 46, contact 60, wire 59, battery 54, wire 58, to the negative 130

brush 64 of the generator G'. Thus, during the intervals that the field 65 of the generator G' is energized current is impressed upon the line circuit in the same direction by the generator G' as the current was caused to flow through such line circuit by the battery 54 before the energization of the relay 48, from which it follows that the successive energization at recurring intervals of the field 65 of the generator G' reverses the direction of current flow periodically through the line conductors 1 and 2, and, therefore, causes actuation of the time meter 9. This meter therefore serves to register the length of time in telechrones between the response of the called subscriber and the restoration of the apparatus at the calling substation to its normal condition by placing the receiver R upon the hook switch H. It is to be noted also that the current generated by the generator G' flows through the battery 54 in a direction opposed to the normal direction of current flow from such battery, and that therefore during the active intervals of the generator G' the battery 54 is charged.

Assume now that the condition of apparatus described above has been produced by a call from the substation A', as a result of which the apparatus at the substation B is connected therewith in the manner above described, and that during such a connection the subscriber at substation A, before making a call, wishes to learn if the party line 1, 2 is busy, he first depresses his key 21, thereby short-circuiting the terminals of the transmitter T, and also short-circuiting the terminals of the setting magnet 13 of his message meter 15, such short-circuit being traced through wire 76, contact 31, switch 21 and wire 84. With the switch 21 in its actuated position the receiver R is removed from the switch H, and the primary winding 25 is thereby connected in circuit with the line wires 1 and 2, as above described, and the subscriber at substation A can hear whether the line is busy. The operation of the switch 21 serves to protect the resetting coil 13 from the flow of current from the line wires 1 and 2 if at this instant it should occur that the direction of current flow in such line wires was that required to separate the armature 16 of the ringer 11 from the contact 20. Thus the subscriber at station A is afforded a means for determining the condition of the party line to which he is connected without having a call charged up against him, but he is unable to hold a conversation at this time since his transmitter T is short-circuited. Were it not for the short-circuiting of the resetting coil 13 during the operation of listening-in to determine whether the line is busy, the armature 19 might be moved to its set position, assuming that the direction of current flow in

the line 1, 2 was proper to cause this result, and this would cause a closure of the contacts 22 and 23, as a result of which the hanging up of the receiver R would complete the circuit through the actuating winding 14; and even if the direction of current flow at this time were not that required to actuate the magnet 14, a subsequent reversal of direction, due to the continued connection at substation A', would serve to actuate the magnet 14, thus advancing the message meter 15 one unit.

It is to be observed that during the entire period of listening-in with the switch 21 depressed, whether the interval be long or short, the time meter 9 is connected in circuit, and thus a means is afforded for indicating the total length of time in telechrones that the apparatus at the substation A is operatively connected, whether as a result of initiating a connection or listening-in on a connection already established. Assuming again that the substation A is the calling substation, and that a connection has been effected with the substation B, at the termination of the conversation the receiver R is placed upon the hook switch H, at which time the armature 19 is in a position closing the contacts 22 and 23, since the first reversal of current in the line wires 1 and 2 resulting from the completed talking circuit serves to move the armature to such position, and a circuit is therefore closed through the actuating winding 14 as follows: The winding 14 is preferably so constructed that under the influence of the permanent magnet 86 it requires current from battery 54 to actuate it rather than current from the generator G', as a result of which the contacts 22 and 23 maintain in closed condition the circuit through the relays 42 and 43 and locking winding 49, as above described, although such circuit is open at the contacts 12 and 28 of the hook switch H. During an inoperative interval of the generator G', current flows as follows: battery 54, wire 59, contact 60, armature 46, locking winding 49, wire 44, relay 42, tip 34, tip spring 5, line wire 1, post 7, wire 77, spring 28, spring 24, wire 85, spring 23, 115 meter 9, line wire 2, sleeve spring 6, sleeve 39, relay 43, wire 45, armature 47, contact 61, wire 62, brush 63, armature of generator G', brush 64, wire 58, back to battery 54. 120 This causes the energization of the actuating coil 14, moving the armature 19 to the position indicated in the drawings, as a result of which the contacts 22 and 23 are separated from each other, thereby opening the circuit through the relays 42 and 43 and the locking winding 49, as a result of which the relay 48 is deenergized—assuming that the subscriber B has hung up his receiver before the subscriber A has done so. If, however, 130

at this time the subscriber B has not hung up his receiver, the relay 48 remains energized, but immediately upon the subscriber B hanging up his receiver, it is deenergized, since the circuit through the energizing winding 55 is opened and the locking winding 49 is at this time not in operating condition.

From the above it will be noticed that the control of the relay 48, after it is once energized, rests with the calling subscriber, since such relay can only be deenergized by opening the circuit through the supervisory relay 42 associated with the answering end of the cord circuit, and this is accomplished when the calling subscriber hangs up his receiver. In this way the calling line is protected from repeated current reversals which would occur if the relay 48 could be repeatedly energized and deenergized by the actuation of the switch hook at the called substation. These repeated current reversals would be particularly annoying to the calling subscriber if he were waiting for a second connection and had his receiver off the switch hook after the conversation with the subscriber B had been terminated. A further undesirable result of leaving the relay 48 under the control of the called subscriber would be that actuation of the relay 48 by the hook-switch at the called substation would result in reversing the direction of current flow in the calling line a greater number of times than would be the case if the reversal were due entirely to the time-controlled mechanism at the exchange, and thus an added registration on the time meter would result, and the meter would indicate the number of telephones as the apparent service given the calling substation, whereas the actual amount of service would be smaller.

As shown in Fig. 2, the units wheel 15^a of the message meter 15 has extending from its face a plurality of pins 15^b, extending toward the ratchet wheel 15^c, secured to the wheel 15^a, which ratchet wheel is sufficiently displaced from the units wheel 15^a that the pins 15^b clear the actuating pawl 15^d carried by the armature 19 of the meter. The armature 19 also carries a rigid projecting arm 19^a adapted to move between two of the pins 15^b when the armature 19 is actuated, in such a manner as to prevent the advance of the units wheel 15^a beyond its proper position to which motion of the armature 19 is intended to move it. The pins 15^b and the arm 19^a thus constitute a mechanism for preventing the overthrow of the units wheel 15^a, due to its inertia. A holding pawl 15^e is provided to engage the ratchet wheel 15^c when the wheel 15^a is advanced, so that one of the pins 15^b is nearly or quite in engagement with the arm 19^a. This provides that the friction of the moving parts may be

made very small and that the adjustment of the actuating pawl may be made sensitive without danger of false operation for either direction of the units wheel 15^a.

While my system is shown herein as applied to a manual telephone system, it is to be understood that it is equally applicable to any telephone system, whether manual or automatic, in which current is supplied at an exchange through suitable means to a connection to operate meters at the substations.

While I have shown my invention in the particular embodiments herein described, I do not, however, limit myself to this construction, but desire to claim any equivalent that may suggest itself to those skilled in the art.

What I claim is:

1. In a telephone system employing a rate for service based upon the number of messages and the duration of conversations originating at substations, the combination of telephone lines extending from substations to an exchange, a time meter at one of such substations for registering the length of time the substation is in use for outgoing messages, a message meter at such substation for recording the number of outgoing connections established and means associated with the message meter and transmitter for the use of the subscriber capable of preventing outgoing transmission and disabling the message meter.

2. In a telephone system employing a rate for service based upon the number of messages and the duration of conversations originating at substations, the combination of telephone lines extending from substations to an exchange, a time meter at one of such substations for registering the length of time the substation talking apparatus is in use for outgoing messages only, a message meter for outgoing messages only also at such substation, means for the use of the subscriber capable of preventing outgoing transmission and disabling the outgoing message meter, said means being further capable of permitting incoming transmission and the operation of the time meter.

3. In a telephone system employing a rate for service based upon the number of messages and the duration of conversations originating at substations, the combination of telephone lines extending from substations to an exchange, a time meter at one of such substations for registering the length of time the substation talking apparatus is in use, a message meter at such substation for recording the number of connections established and means for connecting such apparatus with the line and simultaneously disabling the message meter and the substation transmitter only.

4. In a telephone system employing a rate for service based upon the number of mes-

- sages and the duration of conversations originating at substations, the combination of telephone lines extending from substations to an exchange, a time meter at one of such substations for registering the length of time the substation talking apparatus is in use, a message meter at such substation, means for the use of the subscriber capable of preventing outgoing transmission of voice currents from the substation and disabling the message meter.
5. In a telephone system employing a rate for service based upon the number of messages and the duration of conversations originating at substations, the combination at a substation of talking apparatus, a time meter adapted to record the duration of outgoing messages, a message meter adapted to record the number of outgoing messages, means for simultaneously connecting such apparatus and meters in operative condition, and means for operatively connecting the receiver and time meter without operatively connecting the message meter and transmitter.
6. In a telephone system employing a rate for service based upon the number of messages and the duration of conversations originating at substations, the combination at a substation of talking apparatus, a time meter, a message meter, means for simultaneously connecting such apparatus and meters in operative condition, and means for connecting such apparatus and simultaneously disabling the message meter and transmitter only.
7. In a telephone system employing a rate for service based upon the number of messages and the duration of conversations originating at substations, the combination at a substation of talking apparatus, a time meter, a message meter, means for simultaneously connecting such apparatus and meters in operative condition, and means for operatively connecting such apparatus and simultaneously disabling one of such meters without interrupting incoming transmission.
8. In a telephone system employing a rate for service based upon the number of messages and the duration of conversations originating at substations, the combination at a substation of talking apparatus, a time meter, a message meter and means for simultaneously connecting such apparatus and meters in operative condition and means for operatively connecting the receiver of the talking apparatus and simultaneously connecting in operative condition but one of said meters.
9. In a telephone system, the combination of telephone lines extending from substations to an exchange, one or more of such substations having apparatus comprising a transmitter, a receiver, a time meter auto-
- matically controlled by two different sources of current, controlled by the called subscriber and a message meter, and means for operatively connecting the receiver and one of such meters to the corresponding line 70 without operatively connecting the other meter.
10. In a telephone system, the combination of telephone lines extending from substations to an exchange, one or more of such substations having apparatus comprising a transmitter, a receiver, a time meter and a message meter, and means for operatively connecting the receiver and one of such meters and simultaneously disabling the 80 transmitter and the other meter.
11. In a telephone system, the combination of telephone lines extending from substations to an exchange, one or more of such substations having apparatus comprising a transmitter, a receiver, a time meter and a message meter, means for operatively connecting all of such apparatus to the corresponding line, and means for operatively connecting the receiver and one of such 90 meters and simultaneously disabling the transmitter and the other meter.
12. In a telephone system, the combination of telephone lines extending from substations to an exchange, one or more of such substations having apparatus comprising a transmitter, a receiver, a time meter and a message meter, a hook switch for connecting the meters and talking apparatus with the line conductors, and a switch adapted when 100 operated to short-circuit the transmitter and the message meter without interfering with the operation of the receiver and time meter.
13. In a telephone system, the combination at a substation of a receiver, a transmitter, a time meter, a message meter, and means for operatively connecting the receiver and one of such meters and simultaneously disabling the transmitter and the other meter.
14. In a telephone system, the combination at a substation of a receiver, a transmitter, a time meter, a message meter, means for operatively connecting all of such apparatus to the corresponding line, and means 115 for operatively connecting the receiver and one of such meters and simultaneously disabling the transmitter and the other meter.
15. In a telephone system, the combination at a substation of a receiver, a transmitter, a time meter, a message meter, a hook switch for connecting the meters and talking apparatus with the line conductors, and a switch adapted when 120 operated to short-circuit the transmitter and the message meter without interfering with the operation of the receiver and time meter.
16. In a telephone system, the combination of telephone lines extending from substations to an exchange, two sources of cur- 130

rent supply, a time control for one of said sources, a meter and talking apparatus comprising a receiver and transmitter at one of such substations and means for operatively connecting the receiver with the line without operatively connecting such meter and transmitter.

17. In a telephone system, the combination of telephone lines extending from sub-
10 stations to an exchange, two sources of cur-
rent supply automatically controlled, a time
control for one of said sources, a meter and
talking apparatus at one of such substations
comprising a receiver and transmitter, means
15 for connecting such apparatus and meter in
operative condition and means for connect-
ing the receiver with the line and at the
same time disabling such meter and trans-
mitter.

18. In a telephone system, the combina-
20 tion of a receiver, two sources of current
supply automatically controlled, a time con-
trol for one of said sources, a transmitter, a
meter, and means for operatively connecting
25 the receiver without operatively connecting
the meter and transmitter.

19. In a telephone system, the combina-
30 tion of a receiver, two sources of current
supply automatically controlled, a time con-
trol for one of said sources, a transmitter, a
meter and means for operatively connecting
35 the receiver without operatively connecting
the meter and at the same time disabling the
transmitter.

35 20. In a telephone system, the combina-
tion of a receiver, two sources of current
supply automatically controlled, a time con-
trol for one of said sources, a transmitter, a
meter, means for operatively connecting the
40 receiver, transmitter and meter, and means
for operatively connecting the receiver with-
out operatively connecting the meter and at
the same time disabling the transmitter.

21. In a telephone system, the combina-
45 tion of telephone lines extending from sub-
stations to an exchange, switching mecha-
nism at the exchange for connecting the
lines for conversation and two sources of
50 constant current of different character, a
time meter at one of such substations for
registering the length of time the substation
talking apparatus is in use, a message meter
at such substation automatically recording
55 calls initiated by a calling subscriber, and
means at the exchange operable by the called
subscriber for actuating the time meter, the
operation of such means serving to remove it
from the control of the called subscriber.

22. In a telephone system, the combina-
60 tion of telephone lines extending from sub-
stations to an exchange, switching mecha-
nism at the exchange for connecting the lines
for conversation and two sources of constant
65 current of different character automatically
controlled, a time meter at one of such sub-

stations for registering the length of time
the substation talking apparatus is in use,
a message meter at such substation auto-
matically recording calls initiated by a call-
ing subscriber, and means at the exchange 70
operable by the called subscriber for actua-
ting the time meter, the operation of such
means serving to remove it from the control
of the called subscriber and place it under
the control of the calling subscriber.

23. In a telephone system, the combina-
75 tion of telephone lines extending from sub-
stations to an exchange, switching mecha-
nism at the exchange for connecting the lines
for conversation, a time meter at one of such
80 substations for registering the length of time
the substation talking apparatus is in use, a
message meter at such substation automatic-
ally recording calls initiated by a calling
subscriber, means for connecting the receiver
85 of the talking apparatus with the line with-
out operatively connecting such message
meter, and means at the exchange operable
by the called subscriber for actuating the
time meter, the operation of such means 90
serving to remove it from the control of the
called subscriber.

24. In a telephone system, the combina-
95 tion of telephone lines extending from sub-
stations to an exchange, switching mecha-
nism at the exchange for connecting the lines
for conversation, a time meter at one of such
100 substations for registering the length of time
the substation talking apparatus is in use, a
message meter at such substation automatic-
ally recording calls initiated by a calling
subscriber, means for connecting the receiver
105 of the talking apparatus with the line with-
out operatively connecting such message
meter, and means at the exchange operable
by the called subscriber for actuating the
time meter, the operation of such means 110
serving to remove it from the control of the
called subscriber and place it under the con-
trol of the calling subscriber.

25. In a telephone system, the combina-
115 tion of telephone lines extending from sub-
stations to an exchange, switching mecha-
nism at the exchange for connecting the
lines for conversation, a time meter at one
120 of such substations for registering the
length of time the substation talking appa-
ratus is in use, a message meter at such sub-
station, means for connecting the receiver
of the talking apparatus with the line and
125 simultaneously disabling the message meter,
and means at the exchange operable by the
called subscriber for actuating the time
meter, the operation of such means serving
to remove it from the control of the called
subscriber.

26. In a telephone system, the combina-
130 tion of telephone lines extending from sub-
stations to an exchange, switching mecha-
nism at the exchange for connecting the lines
for conversation, a time meter at one of such
135 substations for registering the length of time
the substation talking apparatus is in use, a
message meter at such substation automatic-
ally recording calls initiated by a calling
subscriber, and means at the exchange operable
140 by the called subscriber for actuating the
time meter, the operation of such means serving
to remove it from the control of the called
subscriber.

lines for conversation, a time meter at one of such substations for registering the length of time the substation talking apparatus is in use, a message meter at such substation, means for connecting the receiver of the talking apparatus with the line and simultaneously disabling the message meter, and means at the exchange operable by the called subscriber for actuating the time meter, the operation of such means serving to remove it from the control of the called subscriber and place it under the control of the calling subscriber.

27. In a telephone system, the combination of telephone lines extending from substations to an exchange, one or more of such substations having apparatus comprising a transmitter, a receiver, a time meter and a message meter, cord circuits at the exchange for connecting the lines for conversation provided with two sources of current of different character, and means at the exchange operable by the called subscriber for actuating the time meter of the calling subscriber, the operation of such means serving to remove it from the control of the called subscriber.

28. In a telephone system, the combination of telephone lines extending from substations to an exchange, one or more of such substations having apparatus comprising a transmitter, a receiver, a time meter and a message meter, cord circuits at the exchange for connecting the lines for conversation provided with two sources of current of different character, and means at the exchange operable by the called subscriber for actuating the time meter of the calling subscriber, the operation of such means serving to remove it from the control of the called subscriber and place it under the control of the calling subscriber.

29. In a telephone system, the combination of telephone lines extending from substations to an exchange, one or more of such substations having apparatus comprising a transmitter, a receiver, a time meter and a message meter, means for operatively connecting the receiver and one of such meters to the corresponding line without operatively connecting the other meter, cord circuits at the exchange for connecting the lines for conversation, and means at the exchange operable by the called subscriber for actuating the time meter of the calling subscriber, the operation of such means serving to remove it from the control of the called subscriber.

30. In a telephone system, the combination of telephone lines extending from substations to an exchange, one or more of such substations having apparatus comprising a transmitter, a receiver, a time meter and a message meter, means for operatively connecting the receiver and one of such meters

to the corresponding line without operatively connecting the other meter, cord circuits at the exchange for connecting the lines for conversation, and means at the exchange operable by the called subscriber for actuating the time meter of the calling subscriber, the operation of such means serving to remove it from the control of the called subscriber and place it under the control of the calling subscriber.

31. In a telephone system, the combination of telephone lines extending from substations to an exchange, one or more of such substations having apparatus comprising a transmitter, a receiver, a time meter and a message meter, cord circuits at the exchange for connecting the lines for conversation, means for operatively connecting all of such apparatus to the corresponding line, means for operatively connecting the receiver and one of such meters and simultaneously disabling the transmitter and the other meter, time controlled impulse sending mechanism, and a relay adapted to be actuated by response of the called subscriber to connect such mechanism to the calling line, such relay having a locking winding in circuit closed through the answering connection of the cord circuit.

32. In a telephone system, the combination of telephone lines extending from substations to an exchange, one or more of such substations having apparatus comprising a transmitter, a receiver, a time meter and a message meter, cord circuits at the exchange for connecting the lines for conversation, means for operatively connecting all of such apparatus to the corresponding line, means for operatively connecting the receiver and one of such meters and simultaneously disabling the transmitter and the other meter, time controlled impulse sending mechanism, and a relay adapted to be actuated by response of the called subscriber to connect such mechanism to the calling line, such relay having a locking winding in circuit closed through the answering connection of the cord circuit and the apparatus at the calling substation.

33. In a telephone system, the combination of telephone lines each extending from a plurality of substations to a central exchange switching mechanism for connecting the lines for conversation, a time controlled source of current, a time meter at one of such substations, for registering the length of time the substation talking apparatus is in use for outgoing messages, a message meter at such substation, automatically recording calls initiated by a calling subscriber, and means at the exchange operable by the called subscriber for actuating the time meter, the operation of such means serving to remove it from the control of the called subscriber.

34. In a telephone system, the combination of telephone lines each extending from a plurality of substations to an exchange, switching mechanism at the exchange for connecting the lines for conversation, a time meter at one of such substations for registering the length of time the substation talking apparatus is in use, a message meter at such substation automatically recording calls initiated by a calling subscriber, means for connecting such apparatus with the line without operatively connecting such message meter, and means at the exchange operable by the called subscriber for actuating

10 the time meter, the operation of such means serving to remove it from the control of the called subscriber and place it under the control of the calling subscriber.

35. In a telephone system, the combination of telephone lines each extending from a plurality of substations to an exchange, switching mechanism at the exchange for connecting the lines for conversation, a time meter at one of such substations for registering the length of time the substation talking apparatus is in use, a message meter at such substation, means for connecting such apparatus with the line and simultaneously disabling the message meter, and means at the exchange operable by the called subscriber for actuating the time meter, the operation of such means serving to remove it from the control of the called subscriber.

36. In a telephone system, the combination of telephone lines each extending from a plurality of substations to an exchange, one or more of such substations having apparatus comprising a transmitter, a receiver, a time meter and a message meter for automatically recording calls initiated by a calling subscriber, means for operatively connecting the receiver and one of such meters to the corresponding line without operatively connecting the other meter, cord circuits at the exchange for connecting the lines for conversation, and means at the exchange operable by the called subscriber for actuating the time meter, the operation of such means serving to remove it from the control of the called subscriber and place it under the control of the calling subscriber.

37. In a telephone system, the combination of telephone lines each extending from a plurality of substations to an exchange, one or more of such substations having apparatus comprising a transmitter, a receiver, a time meter and a message meter, cord circuits at the exchange for connecting the lines for conversation, means for operatively connecting all of such apparatus to the corresponding line, means for operatively connecting the receiver and one of such meters and simultaneously disabling the transmitter

and the other meter, time controlled impulse sending mechanism, and a relay adapted to be actuated by response of the called subscriber to connect such mechanism to the calling line, such relay having a locking winding in circuit closed through the answering connection of the cord circuit.

38. In a telephone system, the combination of telephone lines each extending from a plurality of substations to an exchange, one or more of such substations having apparatus comprising a transmitter, a receiver, a time meter and a message meter, cord circuits at the exchange for connecting the lines for conversation, means for operatively connecting all of such apparatus to the corresponding line, means for operatively connecting the receiver and one of such meters and simultaneously disabling the transmitter and the other meter, time controlled impulse sending mechanism, and a relay adapted to be actuated by response of the called subscriber to connect such mechanism to the calling line, such relay having a locking winding in circuit closed through the answering connection of the cord circuit and the apparatus at the calling substation.

39. In a telephone system, a time controlled source of current, a party line having a plurality of substations, message and time meters at one or more of such stations adapted to be actuated by current reversal in the line, and means for listening in on the line at one or more of the substations when busy without actuating the message meter of said substation.

40. In a telephone system, the combination of telephone lines each extending from a plurality of substations to an exchange, a time controlled source of current at the exchange to operate time meters, a time meter at one of such substations for registering the length of time the substation talking apparatus is in use for outgoing messages, a message meter at such substation and means for listening in on a busy line at such station without actuating the message meter and transmitter of the talking apparatus.

41. In a telephone system, the combination of telephone lines each extending from a plurality of substations to an exchange, a time controlled source of current at the exchange to operate the meters, one or more of such substations having apparatus comprising a transmitter, a receiver, a time meter and message meter and means for listening in on a busy line without actuating the message meter.

42. In a telephone system, the combination of telephone lines each extending from a plurality of substations to an exchange, switching mechanism at the exchange for connecting the lines for conversation, a time controlled source of current at the exchange to operate time meters, a time meter at one

of such substations for registering the length of time the substation talking apparatus is in use for outgoing messages, a message meter at such substation, means at the exchange operable by the called subscriber for actuating the time meter, the operation of such means serving to remove it from the control of the called subscriber and means for listening in on a busy line without actuating the message meter.

43. In a telephone system, the combination of telephone lines each extending from a plurality of substations to an exchange, one or more of such substations having apparatus comprising a transmitter, a time controlled source of current at the exchange to operate the meters, a receiver, a time and a message meter, of cord circuits at the exchange for connecting the lines for conversation, means at the exchange operable by the called subscriber for actuating the time meter, the operation of such means serving

to remove it from the control of the called subscriber and means for listening in on a busy line without actuating the message meter and transmitter of the talking apparatus.

44. In a telephone system comprising a plurality of subscribers' circuits equipped with transmitters, receivers, time meters and message meters, the combination of switching mechanism at the exchange comprising two sources of current, one of which sources is of a periodic character, and means operable by response from the called subscriber to connect said periodic source with the calling subscribers' circuit.

In witness whereof, I hereunto subscribe my name this 29th day of June, A. D., 1910.

GARRISON BABCOCK.

Witnesses:

ALBERT C. BELL,
LEONARD E. BOGUE.
